F. E. ANDERSON

DISRUPTABLE PIN FOR MOTOR STARTING DEVICES

Filed Nov. 30, 1921

INVENTOR
Fred E. Anderson
ATTORNEY
Arthur E. Brown

UNITED STATES PATENT OFFICE.

FRED E. ANDERSON, OF OSAGE CITY, KANSAS, ASSIGNOR OF ONE-HALF TO ALBERT ROBERT, OF OSAGE CITY, KANSAS.

DISRUPTABLE PIN FOR MOTOR-STARTING DEVICES.

Application filed November 30, 1921. Serial No. 518,227.

To all whom it may concern:

Be it known that I, FRED E. ANDERSON, a citizen of the United States, residing at Osage City, in the county of Osage and State of Kansas, have invented certain new and useful Improvements in Disruptable Pins for Motor-Starting Devices; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an engine starting device and particularly to means for cranking the same by manually operated ratchet mechanism.

The primary object of the invention is to provide an inexpensive, simple, durable and efficient device which can be manually operated so as to turn over the crank shaft of the engine to start it, the mechanism being so arranged that in the event of back fire, liability of the person operating the cranking device being injured will be avoided.

There is a novel arrangement of the parts comprising my invention, which will be apparent by reference to the following description in connection with the accompanying drawings, in which—

Fig. 1 is a side elevational view of part of a vehicle with an engine thereon and to which my invention is applied.

Fig. 2 is a fragmentary perspective view of the parts of the engine starter disassociated.

Fig. 3 is a sectional view through the same crank shaft being shown in elevation, and

Fig. 4 is an end view of the engine bed, showing a clip for holding the operating device in its inoperative position.

Referring now to the drawings by numerals of reference:

1 designates an engine base frame which may consist of a tractor frame supported by forward wheels 2 and rear or bull wheels 3. The engine 4 is provided with the usual crank shaft 5, upon which may be mounted a tube or sleeve 6 having at one end a disk 7 with a clamping block 8 integral therewith. The sleeve, the disk and the clamping block may be an integral structure and the

end of the sleeve opposite to that on which is located the disk 7 is provided with threads 9 and is split at 10. When the sleeve is placed upon the crank shaft 5, it may be fastened thereto by a clamping strap 11, 60 which will co-operate with the block 8 to fasten the sleeve to the shaft 5 through the medium of the fastening devices 12 and 13 (see Fig. 2).

Mounted upon the sleeve 6 is an operating lever 14, having a handle 15 and provided with a bearing member 16, the major portion of which is spaced from the lever 14 but secured thereto, as at 17. The bearing member 16 co-operates with the lower 70 end of the operating lever 14 in providing a bearing for the frangible pivot 18 for the dog or pawl 19 carried thereby and having swinging movement between the lever 14 and the member 16. The dog or pawl has a 75 toe portion 20 adapted to engage the ratchet teeth 21 on the ratchet 22, provided with a key 23, which engages the slotted portion 10 of the sleeve 6, the ratchet being secured upon the sleeve by the jam nut 24, which also clamps one end of the sleeve 6 to the shaft 5. Therefore, when the strap 11 is in place and the nut 24 is secured on the threaded end 9 of the sleeve 6, the sleeve and the ratchet will be rigid with the shaft, 80 the lever being guided between one side of the ratchet and the disk 7 and carrying the dog so that it may engage the teeth to rotate the shaft when the lever 14 is swung in one direction as, for example, in a clockwise direction, according to the arrangement shown in Fig. 1.

The dog or pawl can be manipulated by a ratchet lever 25, pivoted to the lever 14 and connected at 26 to the triangular-shaped 95 dog 19.

It will be observed that the teeth on the ratchet wheel 22 are arranged so that the dog may engage with them in one direction but will ride idly over them in the opposite direction. Therefore, when the engine crank has been turned over and the engine starts to operate, the ratchet will ride idly over the toe 20 of the dog 19. Then the lever 14 can be swung down until the ratchet lever 25 comes into contact with the bottom of the clip 27 on the base 1, the clip being in line with the path of movement of the lever 25 so that when the lever rests on the bottom of the clip, the dog will be pulled out of engage- 100 105 110

ment with the teeth and the crank shaft may then continue to rotate as a power medium without interference by the starting mechanism.

5 If, on the other hand, the engine back fires while being manually operated, the dog will swing around until the lever 14 contacts with one of the bull wheels 3 and inasmuch as the pivot 18 is of wood or other material 10 sufficiently fragile to break under the action of the jar of the lever 14 coming in contact with the bull wheel, it will be seen that the starting mechanism will be released from the shaft as soon as the pivot pin 18 is 15 broken, thereby eliminating liability of accident. In this case the bull wheel acts as a bumper for stopping the lever 14.

It will be observed that when the engine 20 has been cranked, the lever 14 can be held in an inoperative position with the dog out of the path of rotation of the ratchet wheel 22 because the lever 14 will be held by the spring arms 28 and 29 of the clip 27 and since the lever 25 will rest on the bottom of 25 the clip, liability of the dog moving into engagement with the ratchet wheel teeth will be avoided.

The device can be readily applied to the 30 ordinary internal combustion engine and it is not limited to tractor engines although it is so shown for convenience, and I do not limit myself to the breakable pin connecting the pawl to the lever although it is so shown, as the fragile pin can be placed elsewhere as, 35 for instance, it can be used for connecting the ratchet wheel to the shaft or sleeve.

In case the device is applied to an engine where it is not convenient to attach directly to the crank shaft, and where there is not a

40 bull wheel to act as a bumper, then the starting device can be mounted on a suitable extension, a suitable bumper provided for breaking the pin in case of a back fire, and a bracket provided to carry the lever 14 in its inoperative position.

45 What I claim and desire to secure by Letters-Patent is:

1. An engine starting device comprising a shaft, a ratchet on the shaft, a lever loose 50 on the shaft, a pawl co-operating with the lever to engage the ratchet, a breakable pivot connecting the pawl to the lever, and means for connecting the shaft to the crank shaft of an engine.

2. An engine starting device comprising 55 a crank shaft engaging sleeve, a ratchet wheel rigid with the sleeve, a manually actuated lever loose on the sleeve, a ratchet wheel-engaging pawl, and a fragile pin connecting the pawl to the lever.

3. The combination with an internal combustion engine, a sleeve rigid on the crank shaft of said engine, a ratchet wheel on the sleeve, a ratchet-operating lever loose on the sleeve, a pawl carried by said lever and adapted to normally engage the teeth of the ratchet wheel, a pawl retracting lever carried by the first named lever, a link rod connecting the pawl retracting lever with the pawl, and a clip on the engine in the path of the swinging movement of the lever whereby the lever may be caused to be engaged by the clip so that the retracting lever will contact therewith to draw the pawl out of engagement with the ratchet wheel.

75 In testimony whereof I affix my signature,

FRED E. ANDERSON.
